UNITED STATES PATENT OFFICE.

THOMAS WILSON, OF PHILADELPHIA, PENNSYLVANIA, ASSIGNOR TO THE PENNSYLVANIA GLOBE GAS LIGHT COMPANY, OF PENNSYLVANIA.

INCANDESCENT GAS-BURNER.

SPECIFICATION forming part of Letters Patent No. 642,407, dated January 30, 1900.

Application filed October 4, 1899. Serial No. 732,460. (No model.)

To all whom it may concern:

Be it known that I, THOMAS WILSON, a citizen of the United States, and a resident of the city of Philadelphia, in the county of Philadelphia and State of Pennsylvania, have invented certain new and useful Improvements in Burners for Welsbach and other Incandescent Lights, of which the following is a specification.

10 The object of the present invention is to provide a burner for Welsbach and other incandescent lights with simple, efficient, and reliable means for regulating the supply to the Bunsen tube in such manner that the 15 regulation of the supply of gas and the regulation of the supply of air are independent of each other and may be effected in any relative quantities for the production of the best results without disturbing the light. To 20 these and other ends the invention comprises the improvements hereinafter described and claimed.

The nature, characteristic features, and scope of the invention will be more fully understood from the following description taken 25 in connection with the accompanying drawings, forming part hereof, and in which—

Figure 1 is a side elevational view of a burner embodying features of my invention. 30 Fig. 2 is a view, principally in central section, drawn to an enlarged scale and illustrating details of construction. Fig. 3 is a top or plan view of Fig. 2, and Fig. 4 is a view illustrating portions of the burner detached.

35 In the drawings, 1 is a Bunsen tube provided near one end and in its side walls with air-inlets. To increase or diminish the ingress of air, there is provided a revolvable perforated sleeve 2, which may be turned so as 40 to admit more or less air into the Bunsen tube, as is well understood by those skilled in the art. Superposed on the gas-supply pipe 3 there is a needle-valve 4, provided with suitable passages, as 5, through which gas 45 escapes from the pipe 3 around the needle-valve 4. The seat 6 of the needle-valve is adjusted endwise of the shank 7 of the needle-valve. As shown, these parts are screw-threaded, and the seat is provided with handles or finger-pieces 8, so that when the valve-seat 50 6 is screwed downward the needle-valve 4 penetrates it and restricts or even interrupts the passage of gas into the Bunsen tube

1, which encircles the valve-seat. When the valve-seat is screwed upward, the needle-valve is withdrawn from this seat and the flow of gas is increased up to its maximum limit. To support the Bunsen tube and prevent turning of the mantle and afford access to the finger-pieces 8, use is made of a yoke 55 9, supported by the pipe 3 and in its turn serving to support the Bunsen tube. The valve-seat 6 works freely through an opening in the yoke.

In use the supply of air to the Bunsen tube 60 is increased or diminished by the appropriate adjustment of the sleeve 2. The supply of gas to the Bunsen tube is adjusted by shifting the seat 6 in respect to the valve 4, as described. It will be noted that the shifting of 65 the valve-seat in no wise operates to affect the adjustment of the air-supply. This is important, because the production of a heating-flame of the proper character is dependent upon the regulation of the air and gas mixture, and the gas-pressure is in cities quite 70 variable, so that the described provisions whereby accurate adjustment of the supply of gas in respect to and independently of the supply of air is essential.

75 It will be obvious to those skilled in the art to which the invention appertains that modifications may be made in details without departing from the spirit thereof. Hence I do not limit myself to the precise construction 80 and arrangement of parts herein set forth and shown in the drawings; but,

Having thus described the nature and objects of my invention, what I claim as new, and desire to secure by Letters Patent, is— 85

In a burner of the type specified the combination of a supply-pipe provided with a needle-valve and with apertures for the passage of gas past the needle-valve, a Bunsen tube provided with means for regulating the 90 ingress of air, a valve-seat adjustably mounted on the shank of the valve and extending into the Bunsen tube and a yoke for supporting the Bunsen tube in fixed position, whereby the regulation of the supply of gas is independent of the regulation of the supply of air, substantially as described.

100 THOMAS WILSON.
